CLAIM

The ornamental design for a combined closure and container for a drying agent, as shown and described.

DESCRIPTION

FIG. 1 is a fragmentary perspective view of a combined closure and container for a drying agent showing our new design, the structure shown in broken lines for illustrative purposes only;

FIG. 2 is a perspective view thereof;

FIG. 3 is a front elevational view thereof;

FIG. 4 is a side elevational view thereof, all sides being identical.

FIG. 2

FIG. 3

FIG. 4
